UNITED STATES PATENT OFFICE.

GEORGE F. SISBOWER, OF EAST ORANGE, NEW JERSEY, AND LOUIS EDWARD PITTONI, OF NEW YORK, N. Y., ASSIGNORS TO NEW YORK COUCH BED COMPANY, OF NEW YORK, N. Y., A CORPORATION OF NEW YORK.

COUCH-HAMMOCK.

1,098,185.

Specification of Letters Patent.

Patented May 26, 1914.

Application filed November 19, 1912. Serial No. 732,365.

To all whom it may concern:

Be it known that we, GEORGE F. SISBOWER, a citizen of the United States, residing at East Orange, in the county of Essex and State of New Jersey, and LOUIS EDWARD PITTONI, a subject of the King of Italy, residing at New York city, county and State of New York, have invented certain new and useful Improvements in Couch-Hammocks, 10 the following being a full, clear, and exact disclosure of the one form of our invention which we at present deem preferable.

For a detailed description of the present form of our invention, reference may be had to the following specification and to the accompanying drawing forming a part thereof, in which—

Figure 1 is a perspective view of our device with certain parts taken away; Figs. 2, 20 3 and 4 show details.

Our invention relates to the mode of suspending the hammock and the attachment of the back rail thereto.

Referring to the drawing, A represents 25 one of the side-bars of a rigid metal mattress frame and B one of the cross-bars thereof to which the usual metallic spring fabric of the mattress is attached.

C represents the upholstery covering the 30 mattress fabric. At each end a vertical strip of fabric D is secured at its lower edge to the cross-bar B and at its upper edge to a bar E pocketed in a hem along that edge. The bar E terminates at each end in a hook 35 and the two hooks are engaged respectively by chains H, H¹ which lead downward to the respective ends of the cross-bar B to which they are secured. There will be four 40 of these chains in all, one at each corner of the mattress frame.

J, J are diagonal chains secured to the bar E and converging to a ring by which the hammock is suspended. To the vertical chain H¹ we attach a clip K (see Figs. 2 and 45 3) of sheet metal adapted to be bent into the links of the chain upon which are riveted two undercut studs k¹ and k² having enlarged heads and contracted necks and adapted to enter a slot S on a U-shaped 50 metal plate R secured to and embracing one end of the back-rail G. By this means the back-rail and the wind guard F attached thereto can be readily secured to or removed from the hammock, and when the rail is in

position it can not be turned on its longitudinal axis although it partakes of such flexibility in its mounting as results from the flexibility of the chain. If desired the studs k, k¹ may be riveted directly to the flexible end strip D through metal plates, as 60 shown in Fig. 4, the chains H, H¹ being omitted. In either case the back-bar will be attached to a flexible end member of the hammock and have a separable connection therewith.

What we claim as new and desire to secure by Letters Patent is:

1. A couch hammock provided with a mattress frame flexible supporting means at each end thereof provided with studs, a 70 back rail, and a member at each end of said back rail to receive said studs to detachably secure said end rail to said supports.

2. A couch hammock provided with a mattress frame, a chain at each end thereof, 75 a member provided with studs secured to each of said chains, a back rail, and a member secured to each end of said rail to receive said studs to detachably secure said rail to said chains.

3. A couch hammock comprising a mattress frame, a chain at each end thereof, a clip secured to each of said chains and provided with studs, a back rail, and a plate secured to each end of said rail and provided 85 with slots to receive said studs.

4. A separable connection between the back-rail and flexible end member of a couch hammock comprising two parts, one part being a plate with separated undercut studs 90 thereon and the other a plate having a slot adapted to receive the said studs.

5. A separable connection between the back-rail and a flexible end member of a couch hammock comprising undercut studs 95 secured to said member and a U-shaped plate embracing the end of the said rail and slotted to receive said studs.

6. A separable connection between the back-rail and supporting chain of a couch 100 hammock comprising a part of flexible metal adapted to be bent into the links of the chain and an engaging part on the end of the back-rail.

7. A couch-hammock provided with a 105 mattress-frame, end-supports each having a rigid upper edge and a flexible intermediate portion, an undercut stud provided with a

back-plate secured to the flexible portion of each end support, and a back rail provided at its end with slotted members for engaging the said studs.

5. 8. A couch-hammock provided with a mattress-frame, end supports each having a rigid upper edge and a flexible intermediate portion, a back-plate secured to the flexible portion of each end-support, a back-rail 10 extending between said flexible portions, and separable connection-devices between each end of the back rail and the adjacent flexible portion, one half of each connection device being carried by said back-plate and the 15 other half by one end of the back rail.

9. A couch-hammock provided with a mattress-frame, end-supports having a rigid upper edge and an intermediate flexible portion, a back-rail having at each end a plate 20 with a slot therein opening downwardly,

and undercut studs secured to the said flexible portion of each end-support and adapted to engage the said slot.

10. A couch-hammock provided with a mattress-frame, end-supports having a rigid 25 upper edge and an intermediate flexible portion, back-plates secured to said flexible portions, studs projecting from said back-plate and a back-rail provided at its ends with slotted plates having a non-twisting en- 30 gagement with said studs.

In witness whereof we have hereunto set our hands, before two subscribing witnesses, this thirteenth day of November, 1912.

GEORGE F. SISBOWER.
LOUIS EDWARD PITTONI.
